UNITED STATES PATENT OFFICE.

EDWARD F. CALDWELL, OF NEW YORK, N. Y., ASSIGNOR TO THE PHOENIX
GLASS COMPANY, OF PITTSBURG, PENNSYLVANIA.

DESIGN FOR A GLOBE OR SHADE.

SPECIFICATION forming part of Design No. 26,641, dated February 16, 1897.

Application filed January 13, 1897. Serial No. 619,124. Term of patent 7 years.

To all whom it may concern:

Be it known that I, EDWARD F. CALDWELL, a citizen of the United States, residing at New York, in the county of New York and State of New York, have invented a certain new and useful Design for a Globe or Shade; and I do hereby declare the following to be a full, clear, and exact description of the invention, such as will enable others skilled in the art to which it appertains to make and use the same.

My invention has relation to designs for globes or shades for lamps, gas, or electric-light fixtures, and has for its object the provision of an article of that class of novel, artistic, and pleasing exterior configuration.

In the accompanying drawings, illustrating my design, Figure 1 is a plan view, and Figs. 2 and 3 are side views, of a globe for gas-lights, the shape of the globe being approximately that of a tulip, that is, it comprises a bulbous body A, merging by a gradual curve into the reversely-curved neck B.

The body A, while its general contour is bulbous, is formed with exteriorly-rounded

ribs a a and wider intermediate rounded panels b b, all of which merge gradually into the smooth outwardly-curved neck B.

The upper edge of the globe is scalloped or formed with alternately wide and narrow curves a' b', which are the resultant of cutting through the ribs a a and panels b b in a direction coinciding with the surface of a cone arranged with its axis coincident with the vertical axis of the globe.

The body of the globe curves inwardly toward the upper end, and the exterior surface of the globe may be suitably etched or otherwise ornamented.

Having described my invention, I claim—

The design for a globe or shade herein described and shown in the accompanying drawings.

In testimony whereof I have affixed my signature in presence of two witnesses.

EDWD. F. CALDWELL.
